UNITED STATES PATENT OFFICE.

WILLIAM H. PENFIELD, OF PELHAMVILLE, NEW YORK.

CAR-HEATING APPARATUS.

SPECIFICATION forming part of Letters Patent No. 374,624, dated December 13, 1887.

Application filed April 1, 1887. Serial No. 233,304. (No model.)

To all whom it may concern:

Be it known that I, WILLIAM H. PENFIELD, of Pelhamville, in the county of Westchester, State of New York, have invented certain new and useful Improvements in Car-Heating Apparatus, of which the following is a specification, reference being had to the accompanying drawing.

The object of my invention is to improve that class of car-heating apparatus designed to extinguish fires in car-stoves when an accident happens, such as is liable to disturb the fire so much as to cause it to communicate to the car.

My improvements consist in the combinations of devices hereinafter described, and succinctly summed up in my appended claim.

The accompanying drawing is an elevation, partly in section, illustrating my invention.

A designates an ordinary car-stove, which may be of any desired pattern.

B designates a water-reservoir located over the stove and filled with water.

C designates a pipe extending through the top of the stove and communicating with the reservoir, so that the water may be discharged from the reservoir into the fire in the stove.

D indicates stay-rods extending from the top to the bottom of the car to secure the reservoir and the stove firmly in place, and the stove and reservoir may, for greater safety, be inclosed within a small room in a car lined with zinc, as is usual in car-construction.

E indicates an ordinary ball-valve ground so as to fit its seat in the lower part of the water-reservoir. This valve is provided with a valve-stem, F, which passes through a guide or brace, G, and through the top of the reservoir, where it is pivotally connected with a lever, H, fulcrumed at I and provided with a fixed weight, K. This lever is connected by

a link, L, to another lever, M, pivoted at N and provided with an adjustable pendent weight, O. The arrangement of the levers and weights is such that ordinarily the weight 45 O is sufficient to keep the valve down tight upon its seat and close the water-opening in the lower part of the reservoir; but should the car be turned over or very seriously shaken or broken up, the weight O would be sure to 50 be displaced, so as to permit the weight K to operate, and thus open the valve and let the water in the reservoir pass into the stove and extinguish the fire.

In order to distribute the water thoroughly 55 in its passage into the stove, I provide a separator, P, within the pipe C. This separator may be of any suitable form; but I prefer one with a conical top, Q, and downwardly-projecting pieces or arms R, so as to break up and 60 distribute the current onto a sieve, S, something like the nozzle of a watering pot. This will more effectively extinguish the fire.

What I claim to be new, and desire to secure by Letters Patent of the United States, is— 65,

The combination of the stove, the water-reservoir, the pipe C, connecting the stove and reservoir and provided with suitable water-distributing devices, the valve E, the brace G, the valve-stem F, that extends 70 through the brace and through the top of the reservoir, the lever H, hinged to the valve-stem and provided with a fixed weight, K, and the lever M, connected to the lever H and provided with an adjustable weight, O, substantially as set forth.

In testimony whereof I have hereunto subscribed my name.

WILLIAM H. PENFIELD.
